UNITED STATES PATENT OFFICE

FRANK S. CHEATHAM, OF SAVANNAH, GEORGIA

DRAFT GEAR

Application filed June 19, 1929. Serial No. 372,133.

This invention relates to improvements in draft gears for railway cars of the class utilizing springs and bearing-shoes and an expanding mechanism for the bearing-shoes acting on buffing or pulling to effect frictional and spring resistance, wherein wedge-shaped friction-blocks coact to form the expanding mechanism as more fully hereinafter set forth.

10 The particular objects in view are to provide, in a gear of this type, means for distending the bearing-shoes and compressing resistance springs thereto connected with variable pressure proportional to the strain, 15 utilizing a pair of wedge-shaped friction-blocks to distend the bearing-shoes and effect compression of the resistance springs, and simultaneously imparting, by means of the coacting, overlapping, wedge-shaped friction-blocks, the surplus energy to one end of the gear when and after the other end of the gear has been activated.

In the drawings annexed—

Fig. 1 is a top plan view of the draft gear 25 as assembled, the parts being in their normal position and the gear being half in full and half in section, the section being taken through the longitudinal center line of the gear;

30 Fig. 2 is an end elevation of the gear as assembled, similarly showing half in full and half in section, the section being taken through the vertical center line of the gear;

Fig. 3 is a side elevation, showing half in 35 full and half in section, the section being taken through the vertical center line of the gear;

Figs. 4, 5 and 6 are views of one of the 40 double web members;

Figs. 7, 8 and 9 are views of the other double web member;

Figs. 10, 11 and 12 are views of one of the 45 shoes 3;

Figs. 13 and 14 are views of the cap or socket for holding spring 8;

Figs. 15 and 16 are views of one of the 50 keys;

Figs. 17 and 18 are views of one of the antifriction rollers for the shoes 3;

Figs. 19 and 20 and 21 are views of one of the housings 4;

Fig. 22 is a group view of the springs 8 and 9.

Referring to the drawings by reference numerals, 1 indicates a bifurcated double wedge-shaped friction-block having a tongue 1^a whereby it may be connected to a car-coupler, either directly or through intermediate means. A double wedge-shaped 55 friction-block 2 works in the bifurcation or longitudinal slot of the friction-block 1 and is connected by suitable means to the other car-coupler. Each of the friction-blocks 1 and 2 is provided with a pair of longitudinal 60 slots 1^b and 2^b, respectively, corresponding slots of the said friction-blocks being opposite one another when the gear is in its normal position.

The wedge-shaped friction-blocks 1 and 2 work against a pair of shoes 3, enclosed in 65 housings 4, whose movement is facilitated by means of rollers 5. The housings 4 are affixed to the car-sills 4' by rivets 4^a or otherwise. The outward movement of the shoes 3 is opposed by springs 9 that tend to restore 70 all the parts of the gear to normal position. The longitudinal slots 1^b and 2^b of the friction-blocks 1 and 2 respectively, are connected by a pair of keys 6. Any action on the 75 part of the said keys is opposed by springs 8, retained by a pair of spring-rests 7 fastened to the extremities of the keys 6.

The operation of the gear is as follows:

When a blow is delivered to the gear on 80 any intermediate car of a train by means of tongue 1^a to the wedge-shaped friction-block 1, the action of the latter forces apart the shoes 3 against the action of the springs 9 causing shoes 3 to act simultaneously against 85 rollers 5 and thus against sides of housings 4 in the momentum direction. The force that each car accepts from the original force is thus divided into two components, first, a lateral component to stabilize resistance and, 90 second, a longitudinal component to create momentum. The keys 6 have their ends projecting through slots in the usual sills of the car. It is optional whether or not these keys shall abut the ends of these slots; in 95 100

Fig. 1 they are shown in abutting relation with the ends of the slots. When the keys thus abut the ends of the slots it will be seen that when either wedge block 1 or 2 is pushed the near key 6 will be immediately unseated from slots in the center sills but the far key will not be unseated until the resistance of the adjacent car causes it to be unseated, i. e., forced toward the other key; but this unseating of the far key will be almost instantaneous as it will take but a fraction of a second to bring into action the resistance necessary to unseat it. When the two keys are thus unseated from the center sills by compression of the springs 8 the keys virtually float in the slots. The action is the same in the reverse direction, as is obvious when either of the wedge members is pulled. It will be observed therefore that the spirit of my idea is that with respect to all the cars in train the force from one car to the other be conveyed from one draw-bar to the other via the continuous coupler stems and not through the center sills of the car. And it will be observed further that whether the action be a pushing action or a pulling action all four springs 9 will be brought into action by reason of the wedging action which the wedge members exert on their shoes 3; and it will be further observed that when both bars 1^a and 2^a are under a push or pull action, four of the wedge faces on the wedges will always be in wedging contact with their companion inclined faces of each of the shoes 3, thus maintaining parallelism of the shoes 3 and compressing all four springs 9 equally. In the case of only one car being buffed or the car at the ends of a train, the action will be minimized to the extent that only one drawbar and wedge will act and the whole force must be taken by this car.

It will be observed that a buffing shock received at the coupler is instantly conveyed in full force to the gear via the coupler stems 1^a and 2^a. The gear immediately is in action, giving to the car the necessary force to move it, taking a portion of the blow through its springs and transmitting the surplus to the other coupler. If both of the couplers are activated at about the same time, all the springs immediately go into action and thus equalize the load and dissipate the strains and take the strains from the car sills. Whereas the foregoing describes the action in a buffing force, it is likewise applicable to a draft action, for in a buffing action the force is against the near key, but in a pull the energy is exerted on the far key. The whole gear action, as far as results are concerned, is exactly the same, with the same capacity in both buffing and pulling blows, the essential and only difference existing in the action of the wedge-shaped friction-blocks 1 and 2 which act in opposite longitudinal directions with the difference in blows. It will be under-

stood that momentum is given to the car through the medium of the friction shoes 3 whose ends abut against the adjacent transverse walls of the casing members 4 through the medium of antifriction rollers 5, it being remembered that the casing members 4 are affixed to the car structure. It will be observed that the proportions of the parts are such that it is impossible for the double-wedge members to pull out of the rigidly-anchored casing 4 even though the springs 9 be compressed to the limit, so that each car will be moved by the force applied to its sills by its own draft-gear.

In accordance with the provisions of the patent statutes, I have herein described the principle of operation of my invention, together with the apparatus which I now consider to represent the best embodiments thereof, but I desire to have it understood that the apparatus disclosed is only illustrative and that the invention can be carried out by other means.

What I claim as new is:

1. In a draft gear, the combination of a casing affixed to the car-structure, a pair of oppositely-movable double wedges, one being bifurcated to receive the other to thus cause them to overlap each other and to have their inclined edges coincident with each other, each of said double wedges being connected to a draw-bar of the car, and spring-pressed double-wedge friction blocks normally pressing against all the adjacent inclined faces of both said wedge members and having their ends in abutting relation with said casing, key means extending through elongated slots in both wedge members, said key means being extended laterally beyond the wedge members and having compressible springs arranged between their respective ends.

2. In a draft gear, the combination of a casing affixed to the car-structure, a pair of oppositely-movable draw-bars having their ends extending into said casing from opposite ends and overlapped, said overlapped ends having their opposite faces shaped to form double wedges, the inclined faces of which are co-incident, said overlapped portions being provided with co-incident slots, keys extending through said co-incident slots and springs interpositioned between these keys to normally press the keys toward the opposite ends of said slots, two pressure shoes, one arranged at each side of said overlapped wedge members and each having four inclined surfaces normally engaging the four adjacent inclined surfaces of both wedge members, the ends of said shoes abutting the end-walls of the casing, and springs forcing said shoes against said wedge members.

In testimony whereof I hereunto affix my signature.

FRANK S. CHEATHAM.
